FIG.1.

FIG.2.

FIG.3.

To all whom it may concern:

Be it known that I, Gerald A. Goessling, a citizen of the United States, and a resident of Richmond Heights, in the county of St. Louis, State of Missouri, have invented a new, original, and ornamental Design for a Combination Coin Purse and Key Holder, of which the following is a specification, reference being had to the accompanying drawing forming a part hereof, in which:

Fig. 1 is a top plan view of a combination coin purse and key holder, showing my new design,

Fig. 2 is a perspective view of the holder, and

Fig. 3 is a vertical cross sectional view taken on the line 3—3 in Fig. 1.

The broken lines are for illustrative purposes only.

I claim:

The ornamental design for a combination coin purse and key holder, substantially as shown and described.
